To all whom it may concern:

Be it known that I, Isolina I. Fig. 4 is another side view thereof with the clamping members in open position;

Fig. 5 is a front view of the clamping member;

Fig. 6 is the reverse view of the clamping member shown in Fig. 5;

Fig. 8 is a front view of the coordinating companion clamping member of the curl clip shown in Figs. 1, 2, 3, and 4, and

The characteristic feature of my design resides in the combination on the bifurcated clip disclosed, of the thumb piece of the instant shape having concave sides, a plain border and knurled center, in association with the narrow band receiving portion, all as shown.

I claim:

The ornamental design for a curl clip, substantially as shown and described.
